Primary Examiner — Jennifer L Rempfer*Assistant Examiner* — Edward P Jones(74) *Attorney, Agent, or Firm* — Dorsey & Whitney LLP(57) **CLAIM**

The ornamental design for a spinal cage, as shown and described.

DESCRIPTION

FIG. 1 shows a front-top isometric view of a spinal cage; FIG. 2 shows a rear-bottom isometric view of the spinal cage of FIG. 1

FIG. 3 shows a front view of the spinal cage of FIG. 1; FIG. 4 shows a rear view of the spinal cage of FIG. 1; FIG. 5 shows a right side view of the spinal cage of FIG. 1; FIG. 6 shows a left side view of the spinal cage of FIG. 1; FIG. 7 shows a top view of the spinal cage of FIG. 1; and, FIG. 8 shows a bottom view of the spinal cage of FIG. 1. The broken lines in FIGS. 1-8 illustrate portions of the spinal cage and form no part of the claimed design.
